Uxa & Buyan, LLP(57) **CLAIM**

The ornamental design for an elliptical exercise machine, as shown and described.

DESCRIPTION

FIG. 1 is a perspective view of a design for an elliptical exercise machine showing our new design.

FIG. 2 is a another perspective view

FIG. 3 is a another perspective view

FIG. 4 is a front elevational view thereof.

FIG. 5 is a rear elevational view thereof.

FIG. 6 is a left side elevational view thereof.

FIG. 7 is a right side elevational view thereof.

FIG. 8 is a top plan view thereof; and,

FIG. 9 is a bottom plan view thereof.

1 Claim, 9 Drawing Sheets(56)
